Geo. S. Prindle, his Atty.

UNITED STATES PATENT OFFICE.

FLORENCE L. PRINDLE, OF PHILADELPHIA, PENNSYLVANIA;

DESIGN FOR FRINGE.

SPECIFICATION forming part of Design No. 13,805, dated March 20, 1883.

Application filed December 15, 1882. Term of patent 7 years.

To all whom it may concern:

Be it known that I, FLORENCE L. PRINDLE, of Philadelphia, in the county of Philadelphia, and in the State of Pennsylvania, have invented an Improved Design for Fringe; and I do hereby declare that the following is a full, clear, and exact description thereof, reference being had to the accompanying drawings, making a part of this specification, in which—

10 Figure 1 is a perspective view of a fringe-block that preferably illustrates my design, and Figs. 2 and 3 are like views of the same with the spiral fluting wholly or partially omitted.

15 My design consists in a fringe-block, A, having preferably a tapering spirally-fluted periphery, which periphery is covered with silk, worsted, or other like material, and such covering arranged in horizontal bands *a*, of light

20 and dark shades. Said bands *a* may be arranged, as shown, with the light shades at the upper and lower ends and the dark shade at

the center; or they may be reversed and the light shade placed at the center. While the periphery of the block A is preferably fluted spirally along its entire length, such spirals may be omitted at the longitudinal center, so as to leave a plain band at such point; or they may be entirely omitted and the entire periphery of said block left plain.

Having thus fully set forth the nature of my invention, what I claim as new is—

A design for fringe, consisting of a round tapering block having its surface covered with alternate horizontal bands of light and dark shades, substantially as specified.

In testimony that I claim the foregoing I have hereunto set my hand this 7th day of December, 1882.

FLORENCE L. PRINDLE.
